UNITED STATES PATENT OFFICE.

HANS F. TIEDKE, OF SAGINAW, MICHIGAN, ASSIGNOR TO BAKER PERKINS COMPANY, INCORPORATED, OF WHITE PLAINS, NEW YORK.

FLOUR DUSTER.

Application filed March 29, 1926. Serial No. 98,206.

In the manufacture of bread, cakes, pastry and other bakery products, the dough or the forming machinery, or both, must be dusted with flour or other powdery or granular materials.

This invention relates to a sifter or duster adapted for use on loaf rounders and other material handling machines for bakeries, although the invention is adapted for many other purposes.

Sprinklers, sifters or dusters of this class usually contain a hopper with a screen bottom, either flat or semi-circular in cross section. These machines are supplied with internal power driven agitating devices, generally in the form of bars mounted on radial arms secured to a central rocking shaft by which the bars are oscillated back and forth crosswise over the surface of the screen.

Gates or plates are usually adjustably applied to the under side of the screen when it is desired to cut off more or less of the working or sifting area. I have found that a great saving of material can be made by employing a duster that will sift very evenly over a large area and in which the rate of sifting or density of shower can be quickly and accurately regulated while the machine is in operation, so as to change at will from a heavy fall to a mere trace.

Another object is to reduce the liability of the operator injuring his fingers by accidentally putting them into the sifter, or on any part of it. Heretofore many accidents have occurred because of the reciprocating paddles or other working parts. In my invention no exposed part has sufficient movement nor is it of such shape as to cause such an accident.

I provide a form of agitator that does not permit the material to pack or arch within the sifter. My improved form of agitator also distributes the wear over the area of the screen so that the life of the screen is prolonged.

With the foregoing and certain other objects in view, which will appear later in the specification, my invention comprises the devices described and claimed and the equivalents thereof.

In the drawings, Fig. 1 is a perspective view, partly broken away to show the reciprocating feed grille.

Fig. 2 is a plan view of the grille. 55

Fig. 3 is an enlarged cross section of a pair of grille bars.

Fig. 4 is a part sectional view of the invention as applied to and driven by a loaf rounding machine. 60

Fig. 5 is an end view of the container.

Fig. 6 is a partial diagrammatic plan view of the driving mechanism shown in Fig. 4.

Fig. 7 is a view of one of the slides used for restricting the area to be dusted. 65

As is clearly shown in the drawings the sifter includes the usual box or container 1 having a screen bottom 2. The screen may be of any desired material and size of mesh. It is preferably flat and may be removably fastened to the container by a frame 3 having cross bars 4 to support the middle area of the screen, as shown in Fig. 4. The side edges of the screen-supporting frame have lateral projections 5 through which removable retaining rods 6 are passed, as illustrated in Fig. 1. By removing both rods the frame 3 can be detached and by removing one rod the frame can be opened by swinging downward, the other rod serving as a hinge pintle. 70

One or more sliding control plates 7 is secured to the under side of frame 3 and supported by screw heads or similar projections, as shown in Figs. 4 and 5. By means of the control plates more or less of the screen area can be covered and rendered inoperative and the area to be dusted can be restricted both as to size and location. 80 85

My invention as applied to a screen bottom duster will now be described. 90

An agitating device distributes the material in the container uniformly over the whole working area of the screen. The agitating device consists of a connected series of spaced wiping or scraping bar members 9, 9, the bottom edges of which are either close to, or actually in contact with the screen. The scraping members may be arranged in any desired configuration, but preferably like the bars of a grille as in Fig. 2. They may be perfectly flat on the bottom, or somewhat troughed or curved as desired, but are preferably substantially planiform so as to be capable of reciprocating, for purposes that will now be described. 95 100

This grille has a movement to-and-fro and its stroke is adjustable to change its ampli-

tude of movement. Several important functions are performed by such a grille, one being to prevent arching in the container. Another function of the grille is to maintain a uniform depth of material upon the entire working area of the screen, and by continually undercutting it, to spread and stir the material comprising the bottom of the pile.

11 The top surface of the pile is thereby kept level and tendency to feed through the screen is the same for all parts of its area, regardless of whether there is much or little material in the container.

12 The grille as it passes and repasses scrapes or wipes over the entire screen area at each stroke, although the length of stroke need not be greater than the distance between two bars 9, 9 of the grille.

13 Full stroke is used when maximum sifting is wanted, because the scraping or rubbing edges then produce greatest sifting effect. At shorter stroke each wiping edge 10 traverses less of its screen area than before and consequently the density of precipitation, or dusting is decreased. With very short travel of the grille the sifting effect becomes that of a mere mist. Any desired rate of sifting between these two extremes may be had by merely altering the length of travel, and whatever the rate, there will be uniform distribution over all parts of the area to be overspread.

14 A still further function of the grille bar when made as in Figs. 2 and 3, with a wide top 11 and a narrow or sharp bottom edge 10, is to prevent arching across the narrow spaces 12 between successive grille bars 9, 9. Arching is avoided because the faces diverge downwardly and afford no place for material to build up between the bars, as is evident in Fig. 3. It is thus kept in relatively loose condition suitable for sifting without any tendency to pack or form lumps.

15 The same idea is carried out in the container structure, as shown in Figs. 4 and 5, where the walls are made downwardly divergent to provide an additional means for preventing any possibility of arching.

Lengthwise back-and-forth movement of the grille is availed of to keep the screen perforations open by producing a tremor or palpitation of the screen at each stroke. The way this is accomplished will now be explained.

16 Various means may be employed, but I prefer the device shown in Fig. 4, where the grille is provided with two upright pins 13 by which it is moved back and forth. The pins pass loosely through holes in a rod 14 that is mounted to slide to-and-fro lengthwise in suitable bearings 15, 16 in the ends of the container.

17 Springs 17 of suitable strength may be in-

terposed between the rod and the top of the grille to yieldingly press the grille down upon the screen.

18 If the grille were moved back and forth very slowly no pulsations of the screen surface would result, but if the grille is brought to a sudden stop at the end of each return stroke, a sharp jar is given the grille and is transmitted over the entire area of the screen, producing a beating or whipping effect in the screen. The stop device may be made in the form of a nut 18 on the end of the reciprocating rod 14 as shown in Fig. 4. An end 19 of the nut may strike any fixed object, as a boss 20 located on the container.

19 The impact of the nut against the boss brings the rod to a sudden stop and the resulting jar in the grille produces the desired jolting action upon the screen. Adjusting the position of the nut on the rod adjusts and regulates the length of stroke of the grille while the machine is in action.

20 The nut can be locked in its adjusted position by any suitable nut lock. A convenient locking device is a slit or kerf 21 cut into the nut perpendicular to the axis and provided with a set screw 22 by which the lip so formed can be made to pinch the threads on the rod.

21 To prevent accidents, a rim 18^a is formed on the nut 18 to cover the opening between the striking faces 19 and 20.

22 The grille-actuating means may be of any suitable design. For purpose of illustration I have shown a convenient drive as used by me in conjunction with a loaf forming machine. Such a machine, shown in Fig. 4, is equipped with a rotatable cam 23 on the shaft of cone 24 of a loaf-molding machine, and on the end of the grille rod 14 in a suitable housing or cross head 25 is a roller 26 adapted to engage the cam. The roller is normally kept in contact with the peaks and also the depressions of the cam by means of a spring 27 compressible between the wall of the container 1 and the cross head 25. By adjusting the nut on the rod the roller can be made to contact with the peaks only, thus causing the grille to exert considerable jarring effect on the screen and preventing the screen from clogging.

23 To the extent set forth in the claims, I have contributed to the art of sifting and dusting machinery, and I have accomplished the objects herein set forth in a practical manner, as exemplified by the preferred embodiment which I have illustrated and described.

24 Having thus described my invention, what I claim and desire to secure by Letters Patent is:

25 1. The combination, in a dusting machine, of a receptacle having a flat screen bottom, with an agitator comprising a grille having spaced wiping members, their sides

beveled and their bottom edges yieldingly pressed upon said screen and actuating means for imparting to said agitator to-and-fro movement over the face of said screen.

2. The combination, in a dusting machine, of a receptacle having a screen bottom, with an agitator comprising a grille having spaced wiping members, their bottom edges close to said screen, actuating means adapted to impart to said agitator back-and-forth movement over the face of said screen, and adjusting means adapted to vary the length of stroke of said grille and to thereby vary the rate of dusting, for the purposes set forth.

3. The combination, in a dusting machine, with a grille and a longitudinally slidable rod adapted to impart to-and-fro movement to said grille, means for varying the length of stroke of said rod comprising an adjustable stop adapted to halt the movement thereof, for the purposes set forth.

4. The combination, in a dusting machine,

of a material container having a screen bottom, connected series of spaced grille bars in substantially planiform arrangement and having their bottom edges close to said screen, actuating means adapted to impart to said bars to-and-fro movement, the length of travel of which is normally equal to substantially the distance between successive bars, and travel-adjusting means for varying the amplitude of said movement to vary the intensity of dusting action.

5. The combination, in a dusting machine, of a material container having a screen bottom, connected series of spaced grille bars in substantially planiform arrangement, actuating means adapted to impart to said bars to-and-fro movement and an adjustable stop member for abruptly halting said bars at various predetermined points in their travel, to cause them to produce agitation of said screen.

In testimony whereof, I affix my signature.

HANS F. TIEDKE.
